CUT RING EXPANDER

Fritz Kuert, Winterthur, Switzerland, assignor to
 Sulzer Freres, Societe Anonyme, Winterthur,
 Switzerland

Application September 17, 1946, Serial No. 697,532
 In Switzerland December 18, 1945

6 Claims. (Cl. 29—223)

1

This invention relates to a device for expanding cut rings, in particular piston rings, and is characterised by an expanding tongs and two gripping arms, each of the latter having a gripping piece to hold one end of the ring and each being connected by two links to an arm of the expanding tongs.

It is preferable to construct the device in such a way that each arm of the expanding tongs, together with the gripper arm linked to it and the links, forms a parallelogram. One of the links to each gripper arm and the two arms of the expanding tongs can have one common pivot point. The arms of the expanding tongs may however also be linked to a connecting body at separate places but in positive running engagement with each other.

The invention is further explained below through two simplified embodiments of it shown in the drawing. Fig. 1 shows an expander in which each arm of the expanding tongs, together with the gripper arm linked to it and the links, forms a parallelogram. Fig. 2 illustrates an expander in which the arms of the expanding tongs are linked at separate spots to a connecting body but are in positive running engagement with each other.

The expanding device shown in Fig. 1 has a two-armed expanding tongs, the arms 1 of which form lever arms, and two gripper arms 2. Each of the gripper arms 2 is fitted at one end with an elongated gripper 3 which extends lengthwise therefrom for holding the end of the cut ring 4. Each gripper arm 2 is linked at two points 5 and 6 to two spaced links 7 and 8 of substantially equal length, whilst these links in their turn are pivotably connected at the points 9 and 10 to a lever arm of the expanding tongs. Except for the pivotal connections 5 and 6, and 9 and 10, the links 7 and 8 are unrestrained. The distances between points 5 and 6 are the same as the distances between points 9 and 10. Each lever arm 1 of the expanding tongs consequently forms with the linked-on gripper arm 2 and the respective links 7 and 8 a parallelogram whose angle may be altered as desired when the gripper 3 is not in use. The distance between the two grippers 3 may in this way be suited to the distance between the two ends of the ring. The front links 7 and the two lever arms 1 of the expanding tongs are linked together at the common pivot point 9. The tongs are opened out by means of a spindle 11 provided with left hand and right hand screw threads and running in nuts 12 and 13 pivotably connected to the lever arms of the tongs.

2

When using the expanding device, with the lever arms 1 of the tongs approached to each other, each of the grippers 3 is brought over an end of the ring 4. By causing the lever arms 1 of the tongs to spread apart by means of the spindle 11, the angular position of the gripper arms 2 with respect to each other is changed. In consequence of the possibility of altering the angles of the parallelogram, the distance between the grippers remains unchanged; it is always equal to the distance between the ends of the rings until the fingers 14 and 15 come both to rest on the surfaces of the ring ends. Until the fingers come into that position, no forces are exerted by the tongs on the ring. As shown in the drawings, the finger 14 engages an inner-face portion of the ring while the finger 15 engages the outer periphery of the ring at a distance spaced from its adjacent cut end.

If the expanding tongs is opened further, from the moment when the fingers come to lie on the ends of the ring, each of the grippers exerts on the ring end held by it two equal but opposite couples. Single forces are not exerted by the grippers on the ends of the ring, since the distance between the two gripper arms can at any time suit itself to the distance between the ends of the rings without any resistance. In consequence of the action of the couples, the ring 4 will be opened against its elastic forces. Then each cross-section of the ring 4 will be stressed only by a pure bending moment, but not by any lateral pull or pressure. It is thus possible, in the case of piston rings (or in the case of other rings which have for instance to be inserted into grooves or removed from them), to prevent over-stressing because of the action of unsuitable forces when opening them.

In the device illustrated in Fig. 2, the two lever arms 1 of the tongs are not linked together at one common pivot point, but separately to two points 16 of a connecting piece 17 and kept in positive running engagement with each other through meshing gear segments. The gripper arms 2 are in linked connection with the points 10 and 18 of the lever arms 1 of the tongs through two links 7 and 8 of different lengths.

The lever arms 1 of the expanding tongs are opened by a pressing tongs consisting of two arms 19 and 20 pivoted at 24 and held open by spring 24 which are linked at the points 21 and 22 to the lever arms of the expanding tongs. By pressing the two handles 19 and 20 of the pressing tongs together the lever arms of the expanding tongs are opened and a ring is thereby expanded.

According to the dimension chosen for the distance between the two pivot points 16 on the connecting piece 17, the length of the links 7 and 8 and the distances between the pivot points 5, 6, 10 and 18, a single force corresponding to requirements can be exerted also on the ring elements, and this may lead to a more favourable distribution of the stresses in the case of special rings.

I claim:

1. An expanding tong device for insertion into an opening and exerting outward pressure on opposite sides thereof including a pair of lever arms, means connecting the lever arms for pivotal motion with respect to one another, a pair of elongated pressure members, one pressure member extending in the same general direction as one of the lever arms and the other pressure member extending in the same general direction as the other lever arm, a pair of separate links pivotally connecting each pressure member to its corresponding lever arm, each link being freely pivoted at one end to a pressure member and at its other end to the corresponding lever arm, corresponding ends of the pressure members being positionable adjacent one another, and means at said corresponding end of each pressure member for engaging the corresponding side of the opening into which it is inserted to cooperatively secure that end of that pressure member to said corresponding side of the opening.
2. An expanding tong device as defined in claim 1 in which a parallelogram is formed by each lever arm together with its corresponding pressure member and the links connecting them.
3. An expanding tong device as defined in claim 1 in which one of the links of each pair and the two lever arms are connected at a common point.
4. An expanding tong device as defined in claim 1 in which the pivotal connection between the lever arms comprises a body and separate spaced pivots for each lever arm and which includes interengaging portions on the lever arms for conjoint movement of them.
5. A cut ring expander comprising a pair of lever arms, means connecting the lever arms for pivotal motion with respect to one another, a pair of elongated gripper members, one gripper

member extending in the same general direction as one of the lever arms and the other gripper member extending in the same general direction as the other lever arm, a pair of otherwise unrestrained separate links pivotally connecting each gripper member to its corresponding lever arm, each link being pivoted at one end to a gripper member and at its other end to the corresponding lever arm, corresponding ends of the gripper members being positionable adjacent one another, and means at said corresponding ends of each gripper member for securing that end of that gripper member to an end of a cut ring.

6. A cut ring expander comprising a pair of lever arms, means connecting the lever arms for pivotal motion with respect to one another, a pair of elongated gripper members, one gripper member extending in the same general direction as one of the lever arms and the other gripper member extending in the same general direction as the other lever arm, a pair of separate links pivotally connecting each gripper member to its corresponding lever arm, each link being freely pivoted at one end to a gripper member and at its other end to the corresponding lever arm, each of said gripper members having at one end thereof a finger extending therefrom in a direction generally longitudinally of the gripper member, the distal end of each finger having an overhanging portion extending therefrom to engage an inner face portion of a cut ring adjacent one end thereof, said end of each gripper member also having a portion spaced from the finger thereof in a direction generally transversely of the gripper member to bear on the outer periphery of the ring at a distance from such end thereof.
